(57) **CLAIM**

The ornamental design for a safety cap for laboratory and consumable containers, as shown and described.

DESCRIPTION

FIG. 1 is a top front perspective view of the safety cap for laboratory and consumable containers in a condition of use, showing our new design;

FIG. 2: is a front elevation view thereof, with the rear elevation view being a mirror image thereof;

FIG. 3 is a right elevation view thereof, with the left elevation view being a mirror image thereof;

FIG. 4: is a top plan view thereof;

FIG. 5: is a bottom plan view thereof; and,

FIG. 6: is another top front perspective view thereof, in another condition of use.

The dash lines in the drawings depict portions of the safety cap for laboratory and consumable containers that form no part of the claimed design.

The short-short-long dash lines in the drawings depict environmental structure that forms no part of the claimed design.
